UNITED STATES PATENT OFFICE.

HENRY C. MILLER, OF MILWAUKEE, WISCONSIN.

FLEXIBLE BINDER-POST FOR LOOSE-LEAF BINDERS.

1,184,979.

Specification of Letters Patent. Patented May 30, 1916.

Application filed November 5, 1915. Serial No. 59,714.

To all whom it may concern:

Be it known that I, HENRY C. MILLER, a citizen of the United States, and resident of Milwaukee, in the county of Milwaukee and State of Wisconsin, have invented certain new and useful Improvements in Flexible Binder-Posts for Loose-Leaf Binders; and I do hereby declare that the following is a full, clear, and exact description thereof.

10 The present invention relates to new and useful improvements in loose leaf binders of that general type including a pair of binder heads and flexible post members connecting the heads and movable into one of the heads. 15 to adjust the capacity of the binder and to provide for clamping the leaves between the heads by reason of the relatively fine degree of adjustment afforded by the flexible posts. Such flexible posts, however, are only capable of a certain limited degree of adjustment and it is therefore the object of the present invention to provide a means for adjusting the relative positions of the binder heads in a manner independent of the adjustment procured by moving the posts into one of the heads, whereby an exceedingly wide scope of adjustment may be had, it being more particularly an object to provide this larger degree of adjustment without interference with the retraction of the flexible posts to procure desired finer degree of adjustment and to procure the aforementioned clamping function of the leaves in the head.

20 It is further an object of the present invention to provide means facilitating the movement of the flexible post sections from the respective binder head in which they are disposed to thus permit expulsion of the post sections from the head by means disposed within the head.

25 With the above and other objects and advantages in view, the invention resides more particularly in the novel combination, arrangement and formation of parts more particularly hereinafter described and particularly pointed out in the appended claims.

30 Reference is had to the accompanying drawings wherein similar characters of reference designate corresponding parts throughout the several views and in which:

35 Figure 1 is a vertical sectional view taken through the head portion of the loose leaf binder and embodying in the present invention. Fig. 2 is a horizontal sectional view 40 taken on the line 2-2 of Fig. 1, through the base head member and showing the adjust-

ing mechanism. Fig. 3 is a transverse sectional view taken on the line 3-3 of Fig. 2.

45 Referring now more particularly to the accompanying drawings, 5 and 6 designate respectively the upper and lower binder heads which are in the form of elongated casings substantially oblong in cross-section and closed at their ends by the solid end blocks, 7. The upper clamping head 5 is provided with a hinge top 8 which is normally held in closed position by the locking rod 9, passed longitudinally into the casing and engaging alined ears 10, carried within the casing and secured thereto and to the cover, this being the usual construction to permit adjustment and manipulation of the binder posts.

50 For receiving the binder posts, the inner side of the upper head 5 is provided adjacent its ends with bearing sleeves 11 extending thereinto, and the corresponding portions of the base head member having outwardly termed sleeve portions 12. The 55 binder posts of the present invention are formed each of a series of short metallic links 13 each formed of a cylindrical section having a slot in one end and a lug on its other end engageable in the slot of the adjacent link whereby a continuously cylindrical body structure is provided. The inner end portions of the bodies and lugs are rounded to permit the posts to flex in one direction only, and the posts are passed 60 through the sleeve 12 and bent inwardly to extend in the base head 6. Each of the flexible post bodies terminates at its end adjacent the upper head 5 in a cylindrical portion 14 having a threaded socket 15 in its 65 end whereby a desired number of rigid extension sections 16 may be connected to provide for adding additional leaves without necessitating an undesired extension of the flexible body portions whereby extension of 70 the flexible body portions may operate to provide "finger room" in manipulating the leaves and to provide for attachments within lesser limits. Disposed within the head 5 is a securing member including a knurled head 75 17, resting against the sleeve 11 and a threaded shank, engageable in the socket of the section 16, or in the section 14 if no extensions 16 are provided.

80 The means for retracting and extending 85 the flexible post bodies comprises a feed screw 19, extending longitudinally in one

side of the base head and bearing at its ends in the end blocks, of the head, this screw being provided with oppositely inclined series of threads with which are engaged carriage blocks 20, of oblong shape whereby they are held against rotation and for sliding movement by abutment with adjacent sides of the head casing. The inner ends of the flexible post bodies terminate in 10 cylindrical sections 21, which are engaged in the blocks and secured. Thus by rotating the feed screw in either direction, the flexible posts will be extended from or retracted into the head. For manipulating the feed 15 screw, the end plugs 7 of the base head are provided with sockets 22 into which extend secured extremities of the feed screw which are engageable by the usual sectional post binder key. Proper movement of the flexible post sections in moving outwardly of 20 the binder head through the openings 12 is insured by a guide shield 23 in the shape of an elbow channel member which is secured in the head 6 at the outer sides of the 25 sleeve 12 and which curves inwardly to the opposite wall of the head. This movement of the post sections is also facilitated by the formation of the end portions of the links and of the said lugs thereof, it being 30 noted that the outer side of each of the lugs and the end of the adjacent link is each curved coincident with the arc of a circle having the pivotal connection of the link as its center whereby a continuous outer 35 curved edge is provided upon bending of the links. An exceedingly simple, readily operated, and compact structure is thus provided as the link of the post between the heads may be adjusted to any degree, adjustment 40 of said posts may thus provide the clamping means for the leaves between the heads and thus obviates the necessity of a spring clamping plate such as is usually provided. "Finger room" between the 45 heads to facilitate insertion or removal of the leaves, may always be had irrespective of the number of leaves held in the binder by means of the provision of the extension sections 16 which will be used in connection 50 with relatively great variation in the width of the leaf bodies held, minor variations being provided for by the flexible adjustment of the posts.

Although the posts have been described 55 as comprising a series of links, I do not desire to limit myself to this structure as it is obvious that the posts could be formed in any manner and of any material to insure desired flexure. It is also obvious that various means could be provided in the base 60 head for adjusting the posts without departing from the spirit of the invention in any manner.

While I have shown and described the 65 binder a crossing a single head wherein the

flexible posts are adapted to travel back and forth for the purpose of extending or retracting the device, it is obvious that I may, in some instances, without departing from the spirit of my invention, provide both of the binder heads with means for receiving the movable ends of the post members and means for extending and retracting the same, thus increasing the scope of adjustment of the posts.

I claim:

1. A loose leaf binder comprising binder heads, and post members each formed of a flexible body having a socketed end to receive extension links and means associated 80 with the other ends of the post members for extending or retracting the posts.

2. A loose leaf binder comprising binder heads, flexible post members connecting the heads comprising a series of links, the said post members having end portions extended into at least one of the heads at approximately a right angle to the connecting portion of said post members, mechanism associated with said end portions whereby they 90 are drawn toward each other or spread apart to lengthen or shorten the head connecting portions, and means for removing or adding links to the flexible posts.

3. A loose leaf binder comprising a binder head, a hollow second binder head provided with openings in its wall adjacent the other head, a flexible post member connected with the first head, and passed through the said openings into the hollow head and directed laterally in said head, and a deflecting member in the hollow head adjacent each opening adapted to engage the outer portion of the post at its bend and means associated with the ends of the posts within the hollow head for extending and retracting said ends.

4. A loose leaf binder comprising binder heads, a hollow second head provided with openings in its wall adjacent the first head, flexible post members connecting the heads and having end sections extended through the openings and directed laterally within the hollow head, said sections comprising each a series of links having mutually engaging lugs and slots at their ends, adjacent sides of the link end and lugs being curved to provide a continuously curved outer edge upon bending, the section deflecting members for the posts disposed within the hollow head adjacent the openings thereof and means associated with the ends of the posts within the hollow head for extending and retracting said ends.

5. A loose leaf binder comprising a binder head, a hollow second head provided with openings in its wall adjacent the first head, flexible post members connected with the first head and passed through the said openings and directed laterally in the second head, means connected with the portions of

the posts within the heads for relatively moving said posts, and curved deflector portions within the hollow binder head adjacent the openings adapted to engage the outer portions of the posts at their bends.

6. A loose leaf binder post comprising a flexible body member having one end portion adapted for association with a binder head to be extended or retracted with respect thereto and a plurality of extension sections adapted for securement to each other and to the other end of the body member.

7. A flexible post for loose leaf binders comprising a series of pivotally connected links, affording a practically continuous cylindrical body, one end of said post being adapted for association with a binder head to be extended or retracted with respect thereto, a plurality of extension sections adapted for mutual connection and for connection with the other end of the post and a head member adapted for connection to said extensions or to said other end of the post.

8. A loose leaf binder comprising a pair of hollow binder heads provided with openings in their adjacent faces, binder posts having certain ends engageable through openings of one head and adapted for extension and retraction with respect thereto,

the other ends of the post being engageable through the openings of the other head, extension sections also engageable through said openings of the other head and adapted for securement with each other and with the post ends and retaining heads adapted to be disposed within the said other binding head and to be connected with the extensible sections or with the said other post ends.

9. In a loose leaf binder the combination with a binder head, and a second hollow binder head of flexible posts having ends extensively connected with the hollow binder head, a plurality of extension links adapted for connection with each other and with the other ends of the flexible posts to form continuations thereof, and head members adapted for connection either with one of the extension sections or the ends of the posts to limit movement of the posts with respect to the first head.

In testimony that I claim the foregoing I have hereunto set my hand at Milwaukee, in the county of Milwaukee and State of Wisconsin, in presence of two witnesses.

HENRY C. MILLER.

Witnesses:

EDWARD M. FRANCE,
Geo. W. Young.

DISCLAIMER

1,184,979.—*Henry C. Miller*, Milwaukee, Wis. FLEXIBLE BINDER POST FOR LOOSE-LEAF BINDERS. Patent dated May 30, 1916. Disclaimer filed February 24, 1930, by the assignee, *Stationers Loose Leaf Company*.

Hereby enters this disclaimer as follows:

Hereby disclaims from the scope of claim 3 any structure except when the post members are cylindrical in form and comprised of links so as to permit them to be flexed sufficiently sharp to make the right angle turn described within the hollow binder head.

Hereby disclaims from the scope of claim 5 any structure except when the flexible post members are cylindrical in form and comprised of links so as to permit them to be flexed sufficiently sharp to make the right angle turn described within the hollow binder head and are connected with the first binder head set forth by headed securing members screw connected axially to the flexible posts.
